[57] ABSTRACT

This invention relates to a device for maintaining a detonator and its associated firing connection in position relative to an explosive charge while the latter is inserted into a previously prepared hole during blasting operations. The device comprises an elongated member divided into two arms by a generally right-angled bend, the free end of one arm having a spike extending substantially parallel to the other arm which has at its free end a clip adapted to frictionally engage a fuse or detonating wire extending roughly parallel to said first arm, said arms being flexible but substantially non-deformable.

FIG. 2

FIG. 1

FIG. 3

1
BLASTING OPERATIONS

This invention relates to blasting operations using dynamite or like sticks as the explosive charge and more particularly the invention relates to a device for maintaining a detonator and its associated fuse or electric wire in position relative to a stick of dynamite while the latter is inserted into a drilled holed therefor.

Devices of this type presently used or proposed are either costly, ineffective or at least difficult to install. It is thus the object of this invention to provide a device which is inexpensive to manufacture, effective in use and simple to install.

In accordance with this invention there is provided a device of the above-described general type comprising an elongated member divided into two arms by a generally right-angled bend, the free end of one arm having a spike extending substantially parallel to the other arm which has at its free end a clip adapted to frictionally engage a fuse or detonating wire extending roughly parallel to said first arm, said arms being flexible but substantially non-deformable.

Further features of the invention provide for the device to be molded from synthetic plastics material, preferably polypropylene, for the arms to be of T-shape in cross-section with the stem of the T on the outside of the right-angled bend, for one of the arms to be provided with an enlarged smooth area at the rear end of the spike. The spike to decreases in cross-sectional area towards its point and is of a cruciform in cross-section, and the clip is a collar having a slot in the side thereof allowing the transverse introduction of a fuse or detonator wire therein.

A preferred embodiment of the invention will now be described by way of example, reference being made to the accompanying drawings in which:

FIG. 1 is an isometric view of the device;

FIG. 2 is a sectional view taken along line A—A in FIG. 1; and

FIG. 3 is an elevation of the device in use.

In this embodiment of the invention the device is molded from polypropylene which has the advantage over polyvinyl chloride which has been previously used in that no chlorine or hydrogen chloride gas is given off when the plastics material is burnt.

The device comprises an elongated member 1 divided into two arms 2 and 3 of different lengths by a right-angled bend 4. The longer arm 3 has at its free end a disc shaped formation 5 carrying a spike 6 extending parallel to, and in the same direction as, the shorter arm 2. This spike 6 is of a cruciform in cross-section and decreases constantly in cross-sectional area towards the point 7 thereof.

The free end of the shorter arm is provided with a sleeve 8 having a slot 9 in the sidewall thereof, the axis of the sleeve being parallel to the longer arm 3. The sleeve and slot are dimensioned such that a fuse or detonator wire may be clipped transversely into the sleeve to be frictionally engaged thereby. Also the sleeve is connected to the arm 2 at its end farthest removed from the spike so that it projects downwardly toward the latter.

The elongated member 1 is made to a T-shape in cross-section with the stem of the T located on the outside of the member as shown clearly in FIG. 2. This shape allows sufficient flexibility while ensuring that

the member will not be permanently deformed under normal bending thereof.

In use, a fuse 10 or detonator wire connected to a detonator 11 is clipped into the sleeve 8 in a position such that the detonator may be inserted to the normal depth in a stick of dynamite 12. The detonator is then inserted and the longer arm flexed such that the point of the spike rests on the outside of the stick of dynamite, the spike is then pushed into the dynamite manually, the outer surface of the disc providing a comfortable area for a person's thumb.

If the spike enters the dynamite too far from the end thereof, the sleeve will tend to enter the dynamite instead of the shorter arm pivoting outwardly about the corner of the stick of dynamite as is the case with presently proposed molded devices.

The invention therefore provides a useful, effective and inexpensive device of this type.

It may be found that the spike above described will tend to pull out of the dynamite and if this is the case, it is easily remedied by removing the portion 13 of one of the "fins" 14 of the spike (defined by the arms of the X) adjacent the disc 5, thus forming a type of barb. The fin nearest the sleeve is preferred for this purpose, since generally the force on the device will be axially away from the dynamite which will cause this barb to dig into the dynamite.

What I claim as new and desire to secure by Letters Patent is:

30 1. A device comprising an elongated member divided into two arms by a generally right-angled bend, the free end of one of said arms having a spike extending substantially parallel to the other of said arms which has at its free end a tubular collar extending parallel to said first arm and having a slot in the side wall thereof is adapted to frictionally engage a fuse or detonating wire extending substantially parallel to said first arm, said arms being flexible and substantially non-deformable.

40 2. A device as claimed in claim 1 in which the device is made as an integral plastics molding.

3. A device as claimed in claim 2 in which the plastics material is polypropylene.

45 4. A device as claimed in claim 1 in which the arms are of T-shape in cross-section with the stem of the T on the outside of the bend.

50 5. A device as claimed in claim 1 in which said one arm is provided with an enlarged smooth area at the rear end of the spike and is arranged transversely thereto.

60 6. A device as claimed in claim 1 in which the spike decreases in cross-sectional area towards its point.

7. A device as claimed in claim 1 in which the connector between the collar and arm to which it is connected is remote from said spike.

55 8. A device comprising an elongated member divided into two arms by a generally right-angled bend, the free end of one of said arms having a spike extending substantially parallel to the other of said arms, said spike having fins defining a shape of cruciform cross-section, one of said fins having an interruption thereon to thereby provide a barb for said spike, the free end of the other of said arms having a clip thereon adapted to frictionally engage a fuse or detonating wire extending substantially parallel to said first arm, said arms being flexible and substantially non-deformable.

65 9. A device according to claim 8 in which said elongate member is made as an integral plastic molding.

10. A device as claimed in claim 9 in which the plastic material is polypropylene.
11. A device as in claim 8 in which the arms are of T-shape in cross-section with the stem of the T being located on the outside of the bend.
12. A device as claimed in claim 8 in which said one

arm is provided with an enlarged smooth area at the rear end of the spike and is arranged transversely thereto.

13. A device as in claim 8 in which the spike decreases in cross-sectional area toward its point.
